RATION OF PENNSYLVANIA.

IGNITION SYSTEM FOR INTERNAL-COMBUSTION ENGINES.

1,292,241.

Specification of Letters Patent.

Patented Jan. 21, 1919.

Continuation in part of application Serial No. 86,236, filed March 23, 1916. This application filed November 7, 1916. Serial No. 129,933.

To all whom it may concern:

Be it known that I, WILLIAM C. BRINTON, Jr., a citizen of the United States, residing at Kennett Square, county of Chester, and

5 State of Pennsylvania, have invented a new and useful Improvement in Ignition Systems for Internal-Combustion Engines, of which the following is a full, clear, and exact description, reference being had to the accompanying drawings, which form a part of

10 this specification.

The objects of my invention are: first, to provide, for internal combustion engines in which the charge in each cylinder is ignited

15 by a plurality of sparks, an ignition system which will insure the absolutely simultaneous production of the sparks, thereby insuring the most perfect ignition of the entire charging mixture; and secondly, to control the ignition by means of a vibrator so constructed as to insure the preservation of proper contact surfaces on the fixed and movable contacts of the vibrator, this construction of the vibrator also possessing

20 utility where each of the engine cylinders is provided with but a single spark plug.

A preferred embodiment of the invention is shown in the accompanying drawings in which—

25 Figure 1 is a diagram of the ignition system, the vibrator and part of the switch apparatus being shown in plan. Fig. 2 is a face view of the movable member of one switch. Fig. 3 is an elevation, partly in section, of the switch apparatus. Fig. 4 is an inverted plan view, partly in section, of the upper members of the switch apparatus. Fig. 5 is a horizontal sectional view through the distributor.

30 A source of current supply α , which may be assumed to be a storage battery, is grounded at one side while its other side is connected with the two primary coils, y , y , corresponding to the two spark plugs w of

35 each engine cylinder A. The coils y , y , are arranged in series, the current passing through them to a binding post a mounted on the base B, which forms a closure for both the main switch apparatus and the

40 switch apparatus for reversing the polarity of the circuit and for closing the circuit

through either the main system (the contact maker and interrupter C) or through the auxiliary or high frequency system (the vibrator D), as hereinafter described.

55

The main switch E turns on a binding post b centrally mounted on the base B and is adapted to connect with either a binding post c (electrically connected through the contact maker and interrupter to ground) or a post d . By shifting the switch E to connect with post d the primary circuit is opened. Posts c and d are mounted on the base B.

60

The base B also carries a binding post e (which is connected with the binding post a through a plug switch G), a binding post f , which leads to ground, a contact g connected to binding post e , a contact h connected with binding post b , and four other contacts 1, 2, 3 and 4. Contact 1 is connected with binding post e , contacts 2 and 3 with opposite poles of the vibrator D, and contact 4 with binding post f .

70

The base B is stationary. Mounted to turn on the cover plate B' of the base is the movable member of the polarity reversing switch F. This member comprises a rotatable hub and disk j of insulating material, carrying an annular bridge piece i of conducting material, which, at four points, is shaped to form contacts i' , of which either opposite two are adapted to engage contacts g and h on the base d . Also carried on said disk are two parallel strips or bridge pieces 5, 6, of conducting material, which are adapted to connect contacts 1, 2, 3 and 4 in a manner to be hereinafter described.

80

Assume that the circuit is closed from the battery α through the primary coils y to the binding post a , that the switch G is closed, that the main switch E connects binding posts b and c , and the rotatable member of the switch F is in such position that strip 5 connects contacts 1 and 2 and strip 6 connects contacts 3 and 4. The current now passes from binding post e to contact 1, thence through strip 5 to contact 2, thence through the vibrator D to contact 3, thence through strip 6 to contact 4, and thence to binding post f and ground. The circuit at this time is not closed through the contact maker and interrupter because no two oppo-

85

90

95

100

site contacts i' are in position to engage contacts g and h .

If the rotatable member of the switch F is given a one-eighth turn, the strips 5 and 6 are brought into such position that they bridge none of the contacts 1, 2, 3 and 4 (thus opening the circuit through the vibrator) and at the same time two opposite contacts i' engage respectively the contacts 10 g and h . Thereupon the current coming to binding post e passes to contact g , thence through plate i to contact h , thence to binding post b , through switch E, to binding post c and contact maker and interrupter C to 15 ground.

If the rotatable member of the switch F is given another one-eighth turn, the contacts i' are again moved out of connection with contacts g and h (thus opening the circuit through the contact maker and interrupter) and strip 6 connects contacts 2 and 4, while strip 5 connects contacts 1 and 3. The current passing to binding post e now passes through contact 1, strip 5 and contact 3, thence through the vibrator, in the reverse direction from that hereinbefore described, thence through contact 2, strip 6, contact 4 and binding post f to ground.

The switch F can be turned only in one direction owing to the engagement of a ratchet m on the hub of its rotatable member with a spring arm m' , as shown in Fig. 4. This construction also operates to stop and hold the switch at the exact position to 35 which it is turned. Hence, whenever switch F is moved into position to close the circuit through the vibrator, it causes the current to flow therethrough in the direction opposite to its flow during the last preceding closure of the circuit through the vibrator.

The contacts 1, 2, 3, 4, g and h are plungers pressed upward by springs n , as shown in Fig. 3, thereby insuring the establishment and maintenance of proper electrical connection between these contacts and the bridge pieces carried by the rotatable member of the switch F.

The main switch E comprises a hub o turnable in a boss o^3 and carrying a handle 50 o' and an arm o^2 . The boss o^3 is cut away to limit the movement of the arm o^2 in opposite directions. The arm o^2 carries a spring pressed plunger p having a convexly rounded end adapted to settle into a concave 55 depression in the contact c when the switch arm is turned to the left, Fig. 1. The hub o is cut away to receive the bent-in portion of a plate q , which connects with the contact b . A leaf spring p' is secured at one end 60 to the plate q and at the other end contacts with the lower face of the hub o . When the switch is in its closed position, the current travels from contact b through plate q , spring p' , arm o^2 and plunger p to contact c .

65 The vibrator D may be of any approved

construction. Thus, it may comprise a binding post r , a core r' , a winding r^2 , an armature r^3 and a condenser r^4 .

On, or actuated by, the regular cam shaft s of the engine is a cam s' which intermittently actuates the contact maker and interrupter C, causing it to intermittently contact with a binding post s^2 , thereby intermittently closing the primary circuit from binding post e through binding post s^2 and 70 contact maker and interrupter C to ground s^3 is a condenser in the condenser circuit s^4 . The contact maker and interrupter B may be of any approved construction, examples of which may be found in the patents issued to me February 23, 1915, No. 1,129,445 and 75 No. 1,129,446, in a patent issued to me July 24, 1917, No. 1,234,275 and in a patent issued to William H. Brown and myself jointly July 24, 1917, No. 1,234,278. 80

The two primary coils y energize respectively the coils z of two secondary circuits. In each secondary circuit is a distributor H, one for each spark-plug of each cylinder. Each distributor is shown provided with six 90 terminals and therefore adapted for use with a six cylinder engine. It will be understood that corresponding terminals of the two distributors are connected respectively to the two spark plugs of the engine 95 cylinder. The distributors, which are on, or actuated by, the regular cam shaft s, need not be of any specific construction, but it is preferred, for reasons set out in my Patent No. 1,227,109, issued May 22, 1917, to employ distributors of the construction set forth therein. The main elements of such a distributor are shown in Fig. 5, the same comprising a holder or cap t , a head t' within the cam and rotatable with the cam shaft 100 s, a central common terminal binding post u , binding posts u' carried by the cap and electrically connected with the several spark plugs, and a distributor plate v carried by the rotatable head t .

In starting the engine, the switch F is moved to throw the vibrator D into circuit, and the switch E is moved into circuit closing position. The circuit will pass through the vibrator until the switch F is given a one-eighth turn to open the circuit through the vibrator and close the circuit through the contact maker and interrupter C, which thereafter is relied upon to continue the engine in operation.

110 However, it will be understood that the engine may be run on the contact maker and interrupter alone, or on the vibrator alone. So far as concerns the accomplishment of the object of creating a plurality of simultaneous sparks, the invention will be operative with either one or the other, or both as described, and even though no provision is made for reversing the polarity of the vibrator. On the other hand, the contact 115 120 125

maker and interrupter and the vibrator, either or both, will work equally well where but a single spark plug is employed in each engine cylinder, in which case there will be 5 of course but one set of primary and secondary coils and one distributor. I do not herein make any claim concerning the combination of the vibrator, with or without the polarity reversing means, and the contact 10 maker and interrupter, as the same forms the subject-matter of other patents, namely: No. 1,227,109 and No. 1,227,110, both issued May 22, 1917.

It will be understood that where I claim 15 a plurality of spark plugs in each cylinder, I do not mean to be confined to two, it being obvious that the construction is readily adaptable to any number of spark plugs by providing a corresponding number of primary coils, and a corresponding number of 20 secondary coils, secondary circuits and distributors.

It may be stated that the main switch E is adapted more particularly for use where 25 the contacts *c* and *d* are connected to different electrical circuits and where the intermediate position is the "off" position, as in my said Patent No. 1,227,110, and while the switch E herein shown is operative with the 30 specific arrangement herein set forth, it will be understood that any ordinary switch may be substituted.

So far as concerns the construction herein shown and described for reversing the polarity of the circuit in the vibrator, this application is division of my said Patent No. 1,227,110.

Having now fully described my invention, what I claim and desire to protect by Letters Patent is—

1. An ignition system for internal combustion engines comprising an engine cylinder, a plurality of ignition devices therein, a primary electric circuit, means to interrupt the current in the primary circuit, distributors corresponding to the several ignition devices in a cylinder, each distributor adapted to intermittently close a secondary circuit through only its corresponding ignition device, and means actuated by the interruption of the primary circuit to induce a flow of secondary current simultaneously through the several distributors.

2. An ignition system for internal combustion engines comprising an engine cylinder, a plurality of ignition devices therein, a primary electric circuit, means to interrupt the current in the primary circuit, terminals connected with the respective ignition devices in the cylinder, circuit closing members one in operative relation with one ignition device terminal and another in operative relation with another ignition device terminal, other terminals connected 60 with the respective circuit closing members,

and means actuated by the interruption of the primary circuit to induce a flow of secondary current simultaneously through the last named terminals respectively and their corresponding circuit closing members and 70 ignition devices.

3. An ignition system for internal combustion engines comprising an engine cylinder, a plurality of ignition devices therein, a primary electric circuit, means to interrupt the current in the primary circuit, a plurality of secondary circuits, means actuated by the interruption of the primary circuit to induce a flow of current simultaneously through the several secondary circuits, and independent distributors in the respective secondary circuits corresponding to and electrically connected with the respective ignition devices, each distributor comprising a circuit closing member adapted to 80 always close the same secondary circuit through the same ignition device of said cylinder.

4. An ignition system for internal combustion engines comprising a plurality of engine cylinders and a plurality of ignition devices in each cylinder, a primary electric circuit, a plurality of secondary circuits, means actuated by the interruption of the primary circuit to induce a flow of secondary current simultaneously through the several secondary circuits, a plurality of series of terminals, the number of said series corresponding to the number of ignition devices in a cylinder and a number of terminals in 90 a series corresponding to the number of cylinders, the terminals of each series being respectively connected to ignition devices in as many different cylinders, and independent distributors, one for each secondary 95 circuit and each series of terminals, each distributor adapted to successively close the circuit through only the terminals of its own series.

5. An ignition system for internal combustion engines, comprising an engine cylinder, a plurality of ignition devices therein, a primary electric circuit, a secondary electric circuit, means to interrupt the current in the primary circuit, a plurality of distributors, and means actuated by the interruption of the primary circuit to induce a flow of secondary current simultaneously through the several distributors, the said means including coöoperating primary and 115 secondary coils so wound as to effect a flow of secondary circuit of the same polarity simultaneously through the several distributors.

6. In an ignition system for internal combustion engines, in combination, a primary circuit, a secondary circuit in operative correlation with the primary circuit, a distributor in the secondary circuit, a shaft adapted to operate the distributor, a vibrator in the 120 130

primary circuit; a switch comprising contacts one connected with the source of supply, another with one pole of the vibrator, a third with the other pole of the vibrator 5 and a fourth with ground, and a switch member carrying bridge pieces adapted in one position to close the circuit between the first and second contacts and between the third and fourth contacts and in another po-

sition to close the circuit between the first 10 and third contacts and the second and fourth contacts, whereby the circuit may be closed through the vibrator in opposite directions.

In testimony of which invention, I have hereunto set my hand, at Philadelphia, Pa., 15 on this 13th day of October, 1916.

WILLIAM C. BRINTON, JR.
